H. M. HANSON

SHOVEL HEATING DEVICE

Filed March 9, 1923

Inventor

Harry M. Hanson.

Gl. St. Louis.

Attorney

UNITED STATES PATENT OFFICE.

HARRY M. HANSON, OF DULUTH, MINNESOTA.

SHOVEL-HEATING DEVICE.

Application filed March 9, 1923. Serial No. 622,867.

To all whom it may concern:

Be it known that I, HARRY M. HANSON, a citizen of the United States, residing at Duluth, in the county of St. Louis and State of Minnesota, have invented certain new and useful Improvements in Shovel-Heating Devices, of which the following is a specification, reference being had therein to the accompanying drawing.

10 This invention relates to power shovels such as commonly used for excavations and the like and has special reference to a novel method of heating same to prevent detrimental sticking of the material being excavated to the shovel, this being the principal object of the invention.

Other advantageous features will appear in the further description of the invention.

In the accompanying drawing forming 20 part of this application and in which like reference characters indicate like parts:

Figure 1 is a side elevation of one of a type of shovel to which my invention may be readily applied;

25 Figure 2 is an enlarged elevation, partly broken away, of a dipper shovel equipped with a form of the invention, and

30 Figure 3 is a perspective view of the inside corner of a dipper shovel having teeth upon the lip thereof, it also being equipped with the improved heating means.

In the process of making excavations, very sticky material, such as clay or the like, is encountered, which is known to result in much annoyance in the handling of same on account of its sticky condition, frequently clogging upon the dipper in such a manner as to render same inefficient. Again when excavations of this class are 40 conducted during cold weather, much annoyance is experienced by damp or wet material freezing in and about the dipper, and, to avoid or prevent these conditions in different forms of dippers, I have installed in 45 the shovel or dipper being used a heating element, which it is apparent may be varied considerably to produce the greatest efficiency.

In Figures 1 and 2 are illustrated a very 50 common type of dipper 1, which is usually provided with a reinforcing lip band 2, and may or may not be provided with protruding teeth, such as illustrated at 3 in Figure 3.

In this plain type of dipper an inner 55 metal lining 4 may be incorporated about the walls of the dipper, particularly the two side walls and the front wall thereof, or in fact it may be found that the front wall alone being provided with the heating element might be sufficient, and intermediate of this lining and the outer wall of the dipper or the lip band 2 thereof as the case may be, is installed a suitable heating element illustrated at 5, it being provided with suitable wire connections through a protecting conduit or pipe illustrated at 6, which may extend longitudinally of the dipper stick 7 and provided with any suitable flexible connection intermediate of the 60 dipper stick and the supporting boom therefor; the electric power being furnished from a source of supply on the shovel supporting mechanism.

In Figure 3 is shown a fragmental portion 70 of a dipper, having teeth mounted thereupon intermediate of which I propose to install an inner lining 8 and between which and to front wall of the dipper is installed the heating element 9 connected in any desired manner to a source of supply, as previously described, and if heat is applied only to such essential parts of the dipper it may in many instances be found ample 75 to overcome the difficulty.

In Figure 3 I have illustrated the reinforcing band 10 as being channelled and having incorporated therein the heating elements 11 which is simply a modification 80 of the construction.

Having thus described my invention, what I claim and desire to secure by Letters Patent, is:

1. The combination with a mechanical shovel, of electric heating elements installed 95 within the walls thereof, and means for supplying constant electric current to the heating elements.

2. In combination, a mechanical shovel of the type described having protruding 100 teeth upon the lip thereof, and an electric heating element permanently installed upon the lip intermediate of the teeth for the purpose described.

3. In combination a power dipper of the 105 type described having a reinforcing lip band about the upper edge thereof and electric heating elements permanently incorpo-

rated within the band for the purpose described.

4. The combination with a mechanical shovel of the type described having a principal digging lip and side walls adjacent to the upper portion thereof, of electric heating elements permanently installed within

said lip and walls for the purpose described.

In testimony whereof I hereunto affix my signature in the presence of two witnesses.

HARRY M. HANSON.

Witnesses:

S. LE BRONSON,
S. GEO. STEVENS.
